William H. Hawley

UNITED STATES PATENT OFFICE.

WILLIAM H. HAWLEY, OF UTICA, NEW YORK.

IMPROVEMENT IN CORES FOR CASTING AXLE-BOXES.

Specification forming part of Letters Patent No. **106,265**, dated August 9, 1870.

To all whom it may concern:

Be it known that I, WILLIAM H. HAWLEY, of the city of Utica, in the county of Oneida and State of New York, have invented a new and improved mode or process of casting iron axle or skein boxes around bearings of soft, or box, or composition metal, so that such bearings and box can be easily reamed down, of which the following is a specification:

My invention relates to the arrangement of a gutter between the edge of a rim upon the interior of an axle or skein box and the adjacent inner edge of a soft, box, or composition metal bearing within said axle or skein box. My invention also relates to the mode of casting this gutter in place; the object of my invention being to separate the inner parts of the said rim and of the adjacent edge of the bearing, and thus to enable the interior surface of the box and its bearing to be reamed out without injuring or dulling the tool used in the reaming.

Figure 1 is a longitudinal section through the center of a newly-cast axle or skein box, showing the arrangement of the gutters or channels which are the subjects of this invention. Fig. 2 is a longitudinal section through the center of the axle or skein box when the rims and bearings have been reamed down, and the gutters reamed out or erased, and said axle or skein is in working order.

A (see Fig. 1 of drawing) is the axle or box. B B are bearings of composition metal resembling bronze. They may, however, be made of soft or box metal and the like. These bearings extend around the interior of the box, their use being to lessen the friction arising from the box revolving upon its axle or skein. C C C C are rims or elevations of the interior of the axle-box. The use of these rims is twofold: first, to secure the composition or soft metal bearing in position; secondly, to support the bearing and protect it from injury by impingement of the axle. D D D, Fig. 1, are gutters within and extending around the interior of the box on each inner edge of the soft or composition metal bearings B B, and situate between them and the rims C C C C. These gutters do not extend the entire thickness of the rims down between

the edge of the composition or soft metal bearings and the rims, so as to separate said rims and bearings entirely, but they extend down the height of the bead formed on the core. The height of this bead may vary according to the quantity of metal which it is desired to dress off or ream down. The object of employing these gutters is to prevent the inner edge of the rim and the inner edge of the bearing from coming together during the operation of casting the box around the bearing, and to thus prevent, at the point where the rim and bearing would meet, their chilling and forming a substance so hard that no tool in present use can effectively cut said hard substance.

My mode of casting the axle or skein box around the bearing is as follows: The bearing or ring B, of a suitable size, is first cast of a composition metal resembling bronze, or of soft, or box, or other metal. The core-box for the axle or skein box is so made as to receive usually two of these bearings. The core is then formed inside of the composition-metal bearings. The core-box is so formed that it leaves a bead of sand on the core on each inner edge of the composition-metal bearings. After the core has been formed with these bearings upon it, it is placed in the flask, and the axle or skein box is then cast around and over the bearings. By means of the sand-bead, already referred to, the inner edge of the bearing B is separated from the inner edge of the rim C or C', and thus the edges of both bearings and of the rims are kept soft, and at the common degree of hardness only, thus enabling the interior of both bearing and rim to be reamed down.

I claim—

The arrangement upon the core, as herein described, of the soft-metal bearings B and the sand-bead, whereby, in casting the box, gutters D D are left between the edges of the soft-metal bearings and the rims C C, substantially as set forth.

WILLIAM H. HAWLEY.
